(57) **ABSTRACT**

A plant packaging system comprising a cover having a base and skirt for packaging a potted plant. The cover optionally comprises a protective sleeve portion which can be detached from the lower portion of the package system once the protective function of the sleeve has been completed. The sleeve has one or a plurality of horizontally or diagonally positioned expansion elements for allowing the skirt portion to extend angularly from the base and/or for allowing expansion of the base portion.

PLANT SLEEVE HAVING AN EXPANDABLE PORTION

CROSS REFERENCE TO RELATED APPLICATIONS

The present application is a continuation-in-part of Ser. No. 09/022,958 filed Feb. 12, 1998 U.S. Pat. No. 5,910,051, issued Jun. 8, 1999, entitled "SLEEVE HAVING A DETACHABLE PORTION FORMING A SKIRT AND METHODS," which is a continuation of U.S. Ser. No. 08/788,616, filed Jan. 27, 1997, entitled "SLEEVE HAVING A DETACHABLE PORTION FORMING A SKIRT AND METHODS," now U.S. Pat. No. 5,749,171, issued on May 12, 1998, which is a continuation-in-part of U.S. Ser. No. 08/237,078, filed May 3, 1994, entitled "SLEEVE HAVING A DETACHABLE PORTION FORMING A SKIRT AND METHODS", now U.S. Pat. No. 5,625,979, issued on May 6, 1997, which is a continuation-in-part of U.S. Ser. No. 08/220,852, filed Mar. 31, 1994, entitled "PLANT PACKAGE HAVING A DETACHABLE SLEEVE AND METHODS", now U.S. Pat. No. 5,572,851, issued on Nov. 11, 1996. The specifications of each of the patents of patent applications listed herein is hereby incorporated herein by reference in their entirety.

STATEMENT REGARDING FEDERALLY SPONSORED RESEARCH OR DEVELOPMENT

Not Applicable

FIELD OF THE INVENTION

This invention generally relates to sleeves and, more particularly, to sleeves used to contain floral groupings or media or used to wrap flower pots containing floral groupings and/or media containing floral groupings, and methods of using same.

BRIEF DESCRIPTION OF THE DRAWINGS

FIG. 1 is an elevational view of a sleeve having detaching elements and horizontal expansion elements constructed in accordance with the present invention.

FIG. 2 is a cross-sectional view of the sleeve of FIG. 1, taken along line 2—2 thereof.

FIG. 3 is a sectional view of another embodiment of a sleeve constructed in accordance with the present invention.

FIG. 4 is a cross-sectional view of a yet another embodiment of a sleeve constructed in accordance with the present invention.

FIG. 5 is an elevational view of a version of the sleeve FIG. 1 with a gussetted bottom.

FIG. 6 is a perspective view of the sleeve of FIG. 1 having a pot disposed therein.

FIG. 7 is a perspective view of the sleeve and pot of FIG. 6 after an upper sleeve portion has been removed.

FIG. 8 is an elevational view of a sleeve having diagonally oriented expansion elements.

DESCRIPTION OF THE PREFERRED EMBODIMENTS

The present invention contemplates a plant packaging system comprising in one embodiment a combination of a protective upper portion and a lower decorative cover portion having a base and skirt for packaging a potted plant. The protective upper portion can be detached from the lower

decorative portion of the plant packaging system once the protective function of the upper portion has been completed, thereby exposing the decorative cover portion and allowing the skirt to extend angularly from the base. The protective upper and lower decorative cover portions may comprise a unitary construction or may comprise separate components which are attached together by various bonding materials prior to disposition of the pot therein.

More specifically, the present invention in a preferred embodiment contemplates a sleeve for covering a pot having an outer peripheral surface. The sleeve comprises (1) a base portion having a lower end, an upper end, an outer peripheral surface, and a horizontally oriented area of excess material (one or more expansion elements) for allowing extension or expansion of a portion of the base portion, and (2) an upper portion extending from the upper end of the base portion and detachable therefrom, and wherein when the upper portion is detached from the upper end of the base portion, the area of excess material expands causing portions of the base portion to extend angularly from the base. In general, the base portion is sized to substantially cover the outer peripheral surface of the pot. The upper portion may be detachable via a detaching element such as perforations, tear strips and zippers. The sleeve may have an extended portion extending from the upper portion for serving as a handle or support device.

The expansion element is integral to the base portion and optionally integral to the upper portion, for allowing expansion of a portion of the base portion into a skirt extending angularly from the base portion when the upper portion is detached from the upper end of the base portion. The expansion element, in a preferred embodiment, may be one or more pleats, one or more folds each having a Z-shaped cross section, one or more accordion-type folds, or other similar types of expandable forms, wherein the folds, creases, or pleats extend circumferentially about at least a portion of the circumference of the sleeve. In another embodiment the sleeve is constructed without a detachable upper portion wherein the sleeve has a base and skirt.

These embodiments and others of the present invention are now described in more detail below.

Shown in FIG. 1 and designated therein by the general reference numeral 10 is a flexible sleeve of unitary construction. The sleeve 10 initially comprises a flexible flat collapsed piece of material which is openable into the form of a tube or tubular sleeve, hereinafter referred to herein as "sleeve". The sleeve 10 may be tapered outwardly from the lower end toward a larger diameter at its upper end. In its flattened state the sleeve 10 has an overall trapezoidal or modified trapezoidal shape, and when opened is substantially frusto-conical to conform. It will be appreciated, however, that the sleeve 10 may comprise variations on the aforementioned shapes or may comprise significantly altered shapes such as square or rectangular, wherein the sleeve 10 when opened has a cylindrical form, as long as the sleeve 10 functions in accordance with the present invention in the manner described herein.

The sleeve 10 has an upper end 12, a lower end 14, an outer peripheral surface 16 and in its flattened state has a first side 18 and a second side 20. The sleeve 10 has an opening at the upper end 12 and may be open at the lower end 14, or closed with a bottom at the lower end 14. The sleeve 10 also has an inner peripheral surface 22 which, when the sleeve 10 is opened, defines and encompasses an inner retaining space 24 as shown in FIGS. 2 and 6. When the lower end 14 of the sleeve 10 has a closed bottom, a portion of the lower end 14

may be inwardly folded to form one or more gussets (such as gusset 26 shown in FIG. 5) for permitting a bottom of an object, such as a potted plant, to be disposed into the inner retaining space 24 of the lower end 14 of the sleeve 10.

The sleeve 10 is generally frusto-conically shaped, but the sleeve 10 may be, by way of example but not by way of limitation, cylindrical, frusto-conical, a combination of both frusto-conical and cylindrical, or any other shape, as long as the sleeve 10 functions as described herein as noted above. Further, the sleeve 10 may comprise any shape, whether geometric, non-geometric, asymmetrical and/or fanciful as long as it functions in accordance with the present invention. The sleeve 10 may also be equipped with drains or ventilation holes (not shown), or can be made from permeable or impermeable materials.

The material from which the sleeve 10 is constructed has a thickness in a range from about 0.1 mil to about 30 mils. Often, the thickness of the sleeve 10 is in a range from about 0.5 mil to about 10 mils. Preferably, the sleeve 10 has a thickness in a range from about 1.0 mil to about 5 mils. More preferably, the sleeve 10 is constructed from a material which is flexible, semi-rigid, rigid, or any combination thereof. The sleeve 10 may be constructed of a single layer of material or a plurality of layers of the same or different types of materials. Any thickness of the material may be utilized as long as the material functions in accordance with the present invention as described herein. The layers of material comprising the sleeve 10 may be connected together or laminated or may be separate layers. Such materials used to construct the sleeve 10 are described in U.S. Pat. No. 5,111,637 entitled "Method For Wrapping A Floral Grouping" issued to Weder et al., on May 12, 1992, which is hereby expressly incorporated herein by reference. Any thickness of material may be utilized in accordance with the present invention as long as the sleeve 10 may be formed as described herein, and as long as the formed sleeve 10 may contain at least a portion of a pot or potted plant or a floral grouping, as described herein. Additionally, an insulating material such as bubble film, preferably one of two or more layers, can be utilized in order to provide additional protection for the item, such as the floral grouping, contained therein.

In one embodiment, the sleeve 10 may be constructed from two polypropylene films. The material comprising the sleeve 10 may be connected together or laminated or may be separate layers. In an alternative embodiment, the sleeve 10 may be constructed from only one of the polypropylene films.

The sleeve 10 may also be constructed, in whole or in part, from a cling material. "Cling Wrap or Material" when used herein means any material which is capable of connecting to the sheet of material and/or itself upon contacting engagement during the wrapping process and is wrappable about an item whereby portions of the cling material contactingly engage and connect to other portions of another material, or, alternatively, itself, for generally securing the material wrapped about at least a portion of the pot. This connecting engagement is preferably temporary in that the material may be easily removed, i.e., the cling material "clings" to the pot.

The cling material is constructed and treated if necessary, from polyethylene such as Cling Wrap made by Glad®, First Brands Corporation, Danbury, Conn.. The thickness of the cling material will, in part, depend upon the size of sleeve 10 and the size of the pot in the sleeve 10, i.e., generally, a larger pot may require a thicker and therefore stronger cling

material. The cling material will range in thickness from less than about 0.1 mil to about 10 mils, and preferably less than about 0.5 mil to about 2.5 mils and most preferably from less than about 0.6 mils to about 2 mils. However, any thickness of cling material may be utilized in accordance with the present invention which permits the cling material to function as described herein.

The sleeve 10 is constructed from any suitable material that is capable of being formed into a sleeve and wrapped about a pot 30 (FIG. 6) and a floral grouping or plant 32 disposed therein. Preferably, the material comprises paper (untreated or treated in any manner), metal foil, polymeric film, non-polymeric film, fabric (woven or nonwoven or synthetic or natural), cardboard, fiber, cloth, burlap, or 10 laminations or combinations thereof. The term "polymeric film" means a man-made polymer such as a polypropylene or a naturally occurring polymer such as cellophane. A polymeric film is relatively strong and not as subject to tearing (substantially non-tearable), as might be the case 15 with paper or foil.

The material comprising the sleeve 10 may vary in color and may consist of designs or decorative patterns which are 20 printed, etched, and/or embossed thereon using inks or other printing materials. An example of an ink which may be 25 applied to the surface of the material is described in U.S. Pat. No. 5,147,706 entitled "Water Based Ink On Foil And/Or Synthetic Organic Polymer" issued to Kingman on Sep. 15, 1992 and which is hereby incorporated herein by reference.

In addition, the material may have various colorings, 30 coatings, flocking and/or metallic finishes, or other decorative surface ornamentation applied separately or simultaneously or may be characterized totally or partially by 35 pearlescent, translucent, transparent, iridescent, neon, or the like, qualities. Each of the above-named characteristics may occur alone or in combination and may be applied to the upper and/or lower surface of the material comprising the sleeve 10. Moreover, portions of the material used in 40 constructing the sleeve 10 may vary in the combination of such characteristics. The material utilized for the sleeve 10 itself may be opaque, translucent, transparent, or partially clear or tinted transparent.

It will generally be desired to use the sleeve 10 as a 45 covering for the pot 30 (FIGS. 6 and 7) having the floral grouping or plant 32 disposed therein. A lower end of the pot 30 is closed but may have holes for permitting water drainage. The term "pot" as used herein refers to any type of 50 container used for holding the floral grouping or plant 32. Examples of pots, used in accordance with the present invention include, but not by way of limitation, clay pots, wooden pots, plastic pots, pots made from natural and/or synthetic fibers, or any combination thereof. The pot 30 is adapted to receive the floral grouping or plant 32 in a retaining space thereof. The floral grouping or plant 32 may 55 be disposed within the pot 30 along with a suitable growing medium described in further detail below, or other retaining medium, such as a floral foam. It will also be understood that the floral grouping or plant 32, and any appropriate growing medium or other retaining medium, may be disposed in the 60 sleeve 10 without the pot 30 wherein the sleeve 10 is used as a pot.

The term "floral grouping" as used herein means cut fresh 65 flowers, artificial flowers, a single flower or other fresh and/or artificial plants or other floral materials and may include other secondary plants and/or ornamentation or artificial or natural materials which add to the aesthetics of the overall floral grouping. The floral grouping or plant 32

generally comprises a bloom or foliage portion and a stem portion. Further, the floral grouping or plant **32** may comprise a growing potted plant having a root portion (not shown) as well. However, it will be appreciated that the floral grouping or plant **32** may consist of only a single bloom or only foliage, or a botanical item (not shown), or a propagule (not shown). The term "floral grouping" may be used interchangeably herein with both the terms "floral arrangement" and "plant". The term "floral grouping" may also be used interchangeably herein with the terms "botanical item" and/or "propagule."

The term "growing medium" when used herein means any liquid, solid or gaseous material used for plant growth or for the cultivation of propagules, including organic and inorganic materials such as soil, humus, perlite, vermiculite, sand, water, and including the nutrients, fertilizers or hormones or combinations thereof required by the plants or propagules for growth.

The term "botanical item" when used herein means a natural or artificial herbaceous or woody plant, taken singly or in combination. The term "botanical item" also means any portion or portions of natural or artificial herbaceous or woody plants including stems, leaves, flowers, blossoms, buds, blooms, cones, or roots, taken singly or in combination, or in groupings of such portions such as a bouquet or floral grouping.

The term "propagule" when used herein means any structure capable of being propagated or acting as an agent of reproduction including seeds, shoots, stems, runners, tubers, plants, leaves, roots or spores.

In accordance with the present invention, a bonding material (not shown) may be disposed on a portion of the sleeve **10** to assist in holding the sleeve **10** to the pot **30** having the floral grouping **32** therein when such a pot **30** is disposed within the sleeve **10** or to assist in closing the upper end of the sleeve **10** or adhering the sleeve **10** to the pot **30** after the pot **30** has been disposed therein. Examples of sleeves with bonding material thereon are disclosed in U.S. Pat. Nos. 5,625,979 and 5,572,851, the specifications of which are hereby specifically incorporated by reference herein in their entirety.

As shown in FIGS. 1, 2, 5 and 6, the sleeve **10** is demarcated into an upper portion **40** and a lower portion **42**. The lower portion **42** of the sleeve **10** is generally sized to contain the pot **30**. The upper portion **40** of the sleeve **10** is sized to substantially surround and encompass the floral grouping or plant **32** in the pot **30** disposed within the lower portion **42** of the sleeve **10** (FIG. 6). The sleeve **10** is demarcated into the upper portion **40** and the lower portion **42** by a detaching element **44** for enabling the detachment of the upper portion **40** of the sleeve **10** from the lower portion **42** of the sleeve **10**. In the preferred version, the detaching element **44** is a plurality of generally laterally-oriented or alternately diagonally-oriented perforations which extend circumferentially across the outer peripheral surface **16** of the sleeve **10** from the first side **18** to the second side **20**. The term "detaching element," as used generally herein, means any element, or combination of elements, or features, such as, but not by way of limitation, perforations, tear strips, zippers, and any other devices or elements of this nature known in the art, or any combination thereof, which enable the tearing away or detachment of one object from another. Therefore, while perforations are shown and described in detail herein, it will be understood that tear strips, zippers, or any other "detaching elements" known in the art, or any combination thereof, could be substituted therefore and/or

used therewith. Other examples of perforation patterns which may be used herein are shown in FIGS. 26-31 in U.S. Pat. No. 5,493,809, the specification of which is incorporated herein by reference in its entirety.

In a preferred embodiment, the lower portion **42** of the sleeve **10** further comprises a base portion **46**, and a skirt portion **48**. The base portion **46** comprises that part of the lower portion **42** which, when the pot **30** is placed into the lower portion **42** (FIG. 6), has an inner peripheral surface which is substantially adjacent to and surrounds the outer peripheral surface of the pot **30**. The skirt portion **48** comprises that part of the lower portion **42** which extends beyond an upper rim **34** of the pot **30** and around at least a portion of the floral grouping or plant **32** contained within the pot **30** and which is left to freely extend at angle, inwardly or outwardly, from the base portion **46** when the upper portion **40** of the sleeve **10** is detached from the lower portion **42** of the sleeve **10** by actuation of the detaching element **44**. The degree of the angle may be zero wherein the skirt portion **48** extends straight up from the base portion **46**. In the intact sleeve **10**, the skirt portion **48** includes an upper peripheral edge congruent with the detaching element **44** which is connected to a lower peripheral edge, also congruent with the detaching element **44**, of the upper portion **40** of the sleeve **10**. In FIGS. 1, 5 and 6, the upper peripheral edge of the skirt portion **48** is congruent with a series of alternately diagonally-oriented lines of perforations which together form a zig-zag pattern and comprise the detaching element **44**.

As shown in FIG. 5, the upper portion **40** of the sleeve **10** may also have an additional, optional, detaching element **50**, indicated as a plurality of vertical perforations for facilitating removal of the upper portion **40**, and which are disposed more or less vertically therein extending between the detaching element **44** and upper end **12** of the sleeve **10**. The upper portion **40** of the sleeve **10** is separable from the lower portion **42** of the sleeve **10** by tearing the upper portion **40** along both the detaching element **50** and the detaching element **44**, thereby separating the upper portion **40** from the lower portion **42** of the sleeve **10**. The lower portion **42** of the sleeve **10** remains disposed as the base portion **46** about the pot **30** and as the skirt portion **48** about the floral grouping or plant **32** forming a decorative cover **54** as shown in FIG. 7 which substantially surrounds and encompasses the pot **30** and decorates the floral grouping or plant **32** contained therein.

It will be understood that equipment and devices for forming floral sleeves are commercially available, and are well known to a person of ordinary skill in the art.

As noted above, the sleeve **10** may have an open or closed lower end **14**. When the lower end **14** is closed, the lower end **14** may have one or more gussets **26** (FIG. 5) formed therein as noted above for allowing expansion of the lower end **14** when an object with a broad lower end such as the pot **30** is disposed therein. In another version of the present invention (not shown), a strip of bonding material may be disposed on a portion of the upper portion **40** of the sleeve **10** generally in the vicinity of the upper end **12** of the sleeve **10** for allowing the upper end **12** to be sealed for enclosing the upper portion **40** of the sleeve **10** about the floral grouping or plant **32** disposed therein. The gusset **26** is intended to be representative of gussets in general. Gussets and their construction are well known in the art of packaging.

The sleeve **10** further includes at least one horizontal expansion element **52**. The horizontal expansion element **52**

is integral to at least one of the base portion **46** and the skirt portion **48** and may extend into the upper portion **40** as shown in FIG. 1. The expansion element **52** functions to allow expansion of a portion of the skirt portion **48** of the sleeve **10** into an extended skirt **56**, such as the skirt **56** of the decorative cover **54** formed therefrom and shown in FIG. 7 which extends angularly from the base portion **46** when the upper portion **40** is detached from the upper end of the skirt portion **48**. The expansion elements **52** in the base portion **46** may also serve to enable the outward expansion of the base portion to conform to the pot **30** or other object placed within the base portion **46**.

Each expansion element **52** defined herein comprises one or more areas of excess material shaped in the form of a pleat, crease, or fold which extends at least partially about the circumference of the sleeve **10**. As used herein, the term "excess material" means an amount of material which has a greater surface area than would actually be necessary to form that portion of the sleeve were that portion of the sleeve actually flattened. The expansion element **52** can expand causing portions of the skirt portion **48** to extend angularly from the base portion **46** forming a skirt **56** and a decorative cover **54** about a portion of the floral grouping or plant **32** in the pot **30** as shown in FIG. 7. The one or more expansion elements **52** may extend from the lower end **14** upward to the skirt portion **48** and beyond, or may only comprise a portion of the base portion **46** (see for example U.S. Pat. No. 5,910,051, the specification of which is hereby incorporated herein by reference).

Shown in FIG. 2 is a cross-sectional view of the sleeve **10** which shows one embodiment of expansion elements designated by the reference numeral **52** which have a z-shape in cross-section. When the upper portion **40** is removed, the expansion elements **52** can expand to cause portions of the skirt portion **48** to extend angularly from the base portion **46** forming a skirt **56** as shown in FIG. 7.

Attention is now drawn to FIG. 3 and to the cross-sectional view of a sleeve **10a** shown therein and to expansion elements shown therein which are designated by the general reference numeral **52a**. The expansion elements **52a** have a pleated shape in cross-section and can expand as described above causing portions of a skirt portion **48a** to extend angularly from a base portion **46a** forming a skirt **56a** similar to that shown above.

Attention is now drawn to FIG. 4 and to expansion elements shown therein which are designated by the general reference numeral **52b**. Sleeve **10b** of FIG. 4 is exactly the same as the sleeve **10** described above except that the sleeve **10b** of FIG. 4 has a plurality of fluted or groove-shaped expansion elements **52b**. As before, the expansion elements **52b** of sleeve **10b** can expand causing portions of a skirt portion **48b** to extend angularly from a base portion **46b** forming a skirt in a decorative cover (not shown).

It will be appreciated by one of ordinary skill in the art that the shapes of the expansion elements **52-52b** described above are but several of the shapes which can be contemplated for the present invention. Other shapes which may be contemplated are gussets, fans, and "accordion-folds" to name but a few.

Further, where used herein, the term "horizontal" expansion element may also include expansion elements which are diagonally oriented in the sleeve. FIG. 8, for example, shows a sleeve **10c** having expansion elements **58** which are diagonally oriented.

Each of the sleeves described herein may further include a support extension (not shown herein but shown for

example in U.S. Pat. No. 5,625,979, which is expressly incorporated herein by reference) which extends away from a portion of an upper end of such sleeve. The support extension may have one or more apertures disposed therein for allowing the sleeve to be supported on a support assembly which may comprise, for example, a pair of wickets for shipment, storage, assembly of the sleeves, placement of a pot within the sleeve, or other functions known in the art. The support extension may have a plurality of perforations or other detaching means for allowing the support extension to be removed from the sleeve after the sleeve has been provided for use as described elsewhere herein. In another version of the invention, and applicable to any of the sleeves described above, or elsewhere herein, a sleeve has a handle for carrying the potted plant package by the sleeve. The sleeve may further comprise a detaching element comprising perforations for removing the handle at a later time.

As noted above, the protective upper portion **40** and lower decorative cover portion **42** of the present invention may comprise a unitary construction, or may comprise separately formed components which are connected together by various bonding materials prior to application of the sleeve **10**, **10a**, **10b** or **10c** about the pot **30**.

Changes may be made in the construction and the operation of the various components, elements and assemblies described herein or in the steps or the sequence of steps of the methods described herein without departing from the spirit and scope of the invention as defined in the following claims.

What is claimed is:

1. A tubular sleeve for covering a plant or a pot having an outer peripheral surface, comprising:
a lower end, an upper end, and a side wall, and an area of excess material comprising one or more preformed creases or folds positioned in a horizontal or diagonal orientation in the side wall for allowing expansion of a portion of the tubular sleeve, and the tubular sleeve initially constructed in a flattened condition.
2. The tubular sleeve of claim 1 further defined as being sized to substantially cover the outer peripheral surface of the pot.
3. The tubular sleeve of claim 1 further defined as constructed from a material having a thickness in a range of from about 0.1 mil to about 30 mils.
4. The tubular sleeve of claim 1 further defined as constructed from a material selected from the group consisting of treated or untreated paper, cellophane, metal foil, polymer film, non-polymer film, cardboard, fiber, cloth, burlap, and laminations or combinations thereof.
5. The tubular sleeve of claim 1 wherein the area of excess material further comprises one or a plurality of pleats, one or a plurality of folds each having a z-shaped cross section, or one or a plurality of accordian-type folds.
6. The tubular sleeve of claim 1 wherein the lower end is open.
7. The tubular sleeve of claim 1 wherein the lower end is closed.
8. The tubular sleeve of claim 7 wherein the closed lower end has a gusset therein.
9. The tubular sleeve of claim 7 having a drain hole therein.
10. The tubular sleeve of claim 1 having a bonding material thereon for adhering to the pot after the pot has been disposed within the tubular sleeve.
11. A tubular sleeve for covering a plant or a pot having an outer peripheral surface, comprising:
a base portion having a lower end, an upper end, and a side wall, the side wall comprising an area of excess

material comprising one or more preformed creases or folds positioned in a horizontal or diagonal orientation for allowing expansion of a portion of the base portion; and

a skirt portion attached to the base portion and having an upper end and extending a distance beyond the upper end of the base portion; and wherein the tubular sleeve is initially constructed in a flattened condition.

12. The tubular sleeve of claim 11 wherein the base portion is further defined as being sized to substantially cover the outer peripheral surface of the pot.

13. The tubular sleeve of claim 11 further defined as constructed from a material having a thickness in a range of from about 0.1 mil to about 30 mils.

14. The tubular sleeve of claim 11 further defined as constructed from a material selected from the group consisting of treated or untreated paper, cellophane, metal foil, polymer film, non-polymer film, cardboard, fiber, cloth, burlap, and laminations or combinations thereof.

15. The tubular sleeve of claim 11 wherein the area of excess material further comprises one or a plurality of pleats, one or a plurality of folds each having a z-shaped cross section, or one or a plurality of accordion-type folds.

16. The tubular sleeve of claim 11 wherein the lower end is open.

17. The tubular sleeve of claim 11 wherein the lower end is closed.

18. The tubular sleeve of claim 17 wherein the closed lower end has a gusset therein.

19. The tubular sleeve of claim 17 having a drain hole therein.

20. The tubular sleeve of claim 11 having a bonding material thereon for adhering the tubular sleeve to the pot after the pot has been disposed within the tubular sleeve.

21. A tubular sleeve for covering a plant or pot having an outer peripheral surface, comprising:

a lower portion initially having a flattened condition and a side wall having a lower end, an upper end, and an area of excess material comprising one or more preformed creases or folds positioned in a horizontal or diagonal orientation in the sidewall for allowing expansion of a portion of the lower portion; and

an upper portion from the upper end of the lower portion and detachable therefrom.

22. The tubular sleeve of claim 21 wherein the lower portion comprises a base portion sized to substantially cover the outer peripheral surface of the pot.

23. The tubular sleeve of claim 21 wherein the lower portion further comprises a skirt portion which extends from the base portion.

24. The tubular sleeve of claim 1 further defined as constructed from a material having a thickness in a range of from about 0.1 mil to about 30 mils.

25. The tubular sleeve of claim 21 further defined as constructed from a material selected from the group consisting of treated or untreated paper, cellophane, metal foil, polymer film, non-polymer film, cardboard, fiber, cloth, burlap, and laminations or combinations thereof.

26. The tubular sleeve of claim 21 wherein the upper portion is detachable via a detaching element selected from the group consisting of perforations, tear strips and zippers.

27. The tubular sleeve of claim 21 wherein the area of excess material further comprises one or a plurality of pleats, one or a plurality of folds each having a z-shaped cross section, or one or a plurality of accordion-type folds.

28. The tubular sleeve of claim 21 wherein the lower end is open.

29. The tubular sleeve of claim 21 wherein the lower end is closed.

30. The tubular sleeve of claim 29 wherein the closed lower end has a gusset therein.

31. The tubular sleeve of claim 29 having a drain hole therein.

32. The tubular sleeve of claim 21 having a bonding material thereon for adhering the tubular sleeve to the pot after the pot has been disposed within the tubular sleeve.

33. A tubular sleeve for covering a plant or a pot having an outer peripheral surface, the tubular sleeve initially having a flattened condition, comprising:

a base portion having a lower end, an upper end, and a side wall, the side wall comprising an area of excess material comprising one or more preformed creases or folds positioned in a horizontal orientation for allowing expansion of a portion of the base portion;

a skirt portion attached to the base portion and having an upper end and extending a distance beyond the upper end of the base portion; and

an upper portion attached to the upper end of the skirt portion and detachable therefrom.

34. The tubular sleeve of claim 33 wherein the base portion is further defined as being sized to substantially cover the outer peripheral surface of the pot.

35. The tubular sleeve of claim 33 further defined as constructed from a material having a thickness in a range of from about 0.1 mil to about 30 mils.

36. The tubular sleeve of claim 33 further defined as constructed from a material selected from the group consisting of treated or untreated paper, cellophane, metal foil, polymer film, non-polymer film, cardboard, fiber, cloth, burlap, and laminations or combinations thereof.

37. The tubular sleeve of claim 33 wherein the upper portion is detachable via a detaching element selected from the group consisting of perforations, tear strips and zippers.

38. The tubular sleeve of claim 33 wherein the means for extending further comprises one or a plurality of pleats, one or a plurality of folds each having a z-shaped cross section, or one or a plurality of accordion-type folds.

39. The tubular sleeve of claim 33 wherein the lower end is open.

40. The tubular sleeve of claim 33 wherein the lower end is closed.

41. The tubular sleeve of claim 40 wherein the closed lower end has a gusset therein.

42. The tubular sleeve of claim 40 having a drain hole therein.

43. The tubular sleeve of claim 33 having a bonding material thereon for adhering the tubular sleeve to the pot after the pot has been disposed within the tubular sleeve.

UNITED STATES PATENT AND TRADEMARK OFFICE
CERTIFICATE OF CORRECTION

PATENT NO. : 6,295,760 B1
DATED : October 2, 2001
INVENTOR(S) : Donald E. Weder

Page 1 of 1

It is certified that error appears in the above-identified patent and that said Letters Patent is hereby corrected as shown below:

Title page,

Item [57], **ABSTRACT**,

Lines 1-9, delete from "A" to "portion." and substitute therefore the following paragraph:

-- A sleeve comprising a lower portion having a base portion and a skirt portion for packaging a floral grouping or plant. The sleeve optionally comprises a protective upper portion which can be detached from the lower portion of the sleeve once the protective function of the upper portion has been completed. The sleeve has one or a plurality of horizontally or diagonally positioned expansion elements for allowing the skirt portion to extend angularly from the base and/or for allowing expansion of the base portion. --

Column 9,

Line 9, after the first occurrence of "portion" and before "from" add -- extending --.
